UNITED STATES PATENT OFFICE.

DANIEL WEBSTER SHIEK AND CARY OBERLIN COLE, OF GRAND VIEW, IOWA.

MECHANICAL AUTOMATIC CIGAR-SELLER.

SPECIFICATION forming part of Letters Patent No. 296,468, dated April 8, 1884.

Application filed May 22, 1883. (Model.)

To all whom it may concern:

Be it known that we DANIEL W. SHIEK and CARY O. COLE, of Grand View, in the county of Louisa and State of Iowa, have invented 5 certain new and useful Improvements in Mechanical Automatic Cigar-Sellers; and we do hereby declare the following to be a full, clear, and exact description of the invention, such as will enable others skilled in the art to which it pertains to make and use it, reference being had to the accompanying drawings, which form part of this specification.

Our invention relates to an improvement in mechanical automatic cigar-sellers; and it consists in the combination and arrangement of devices that will be more fully set forth hereinafter.

In the accompanying drawings, Figure 1 is a side elevation of my invention, the case, 20 cigar-box, and inclined way being represented in dotted lines, the machine being here shown in its normal position. Fig. 2 is a similar view of the machine in the act of dispensing a cigar. Fig. 3 is a plan view of the operating mechanism drawn on the angle indicated by arrow of Fig. 1. Fig. 4 is a vertical cross-section on the line *x x*, Fig. 3. Figs. 5, 6 are detail views of the coin-releasing mechanism. Fig. 7 is a section on the line *y y*, Fig. 3.

30 A represents a rock-shaft, which is journaled in suitable standards, B, which project from the base of the case C. To this shaft is secured the circular disks D, near the ends thereof, which disks are connected by the outer segment, E, and by the inner smaller segment, F, which is situated at a suitable distance above the segment E, nearer to the shaft.

Pivoted between the disks D upon the pivot 40 G is a segment, H, which has secured near its upper edge the concave receiver I, which receiver is provided with the slot K, and has secured to it a retractile spring, L, the upper end of the spring being secured to the lower edge of the segment E, the function of which 45 spring is to keep the receiver normally in the position shown in Fig. 4.

Extending through the disks D, and journaled therein at a point in close proximity to the lower edge of the pivoted segment H, is a rock-shaft, M, which has a crank, N, formed at its 50 inner end, as shown.

Extending up from the base of the case, at a suitable point between the disks D, is a standard, O, which is provided at its upper end with a cam, P, which is a quarter-circle on its 55 rear side, as at Q, and has its outer side concave, as at R, this cam being normally almost in contact with the segment F.

Extending from the base of the case up to the shaft is a curved delivery-board, S, the function of which is to convey the cigars, as they are discharged upon it from the receiver, to within reach of the person operating the machine and paying therefor.

Projecting from the rock-shaft M up through 60 the slot K, formed in the receiver I, is a tappet-rod, T, the function of which is to bear against the receiver at the inner end of the slot, and to cause the crank N to perform the function to be set forth hereinafter.

Rigidly secured to the shaft A at the inner 70 end thereof, between the disk D and the standard B, is a U-shaped arm, U, the lower ends of the arms being connected to the shaft, while the upper curved portion thereof conforms in 75 size and shape to the coin which represents the value of each of the cigars to be dispensed. The standard is likewise provided with a curved oblique extension, B', which corresponds in size and shape to the curved end of 80 the arm U, the oblique portion of which extension being parallel to the normal position of the arm U, the curved portion thereof being provided with a slot, B'', through which the coin passes when paid by the person operating the machine, the coin being received and guided by the inclined trough B'', which is made of the exact width of the slot, the slot B'' being of suitable size to exactly admit the coin, the price at which the cigars are to be 85 sold.

Loosely journaled upon the shaft A between the disk D and the arm U are the levers V W. The lever V has its outer end bent at right angles, which bent portion is normally in contact with the under side of the curved portion of the oblique extension B'. The opposite end of the lever is provided with a tappet-pin, V', extending from the inner side thereof, and adapted to be operated by the lever W. The 95 lever V is held normally in the position shown in Figs. 1 and 5 by the upper end of the spring 100

X, which is wrapped around the pin X', with which the disk D is provided, the lower end of this spring X pressing against the under side of the lower end of the lever W. This 5 lever W is provided with the concave cut-away portion W'. On its rear side, and at a suitable point above this cut-away portion, is made a notch, W'', in which notch the crank N of the rock-shaft M normally engages.

10 Loosely pivoted upon the shaft A, midway between the ends of the arm U, is the lever Y, which is preferably V-shaped, and is provided on its inner upper end with an extension, Y', which is normally in contact with the dependent 15 ears U' of the arm U, the lever being notched, as at Y'', and provided with a finger, Y'', which is designed to project sufficiently over the upper side of the lower edge of the coin conveyed through the slot to cause it to 20 engage therewith.

Reciprocating in the case is a rod, 1, which is provided at its outer end with a knob, 2, and has secured to its inner bent end a connecting-lever, 3, which lever is connected to 25 the upper end of the lever 4, fulcrumed at 5, the lower end of this lever 4 having pivoted to it, at 6, the connecting-rod 7, which is pivoted to the lower end of the arm Y, as at 8. Connected to this connecting-rod 7 is a retract- 30 able spring, 9, the outer end of which is secured to the inner side of the front side of the case, the function of which spring is to keep the operating parts normally in the position shown in Fig. 1.

35 The operation of our invention is as follows: The box containing the cigars to be sold is placed upon the inclined board C' of the case C, (shown in dotted lines,) by means of which arrangement the cigars are allowed to roll out 40 of the box down the trough and into the receiver I, which is of sufficient size to hold only one cigar at a time. A person wishing to purchase a cigar places a nickel or other coin which has been designated as the value of the cigars 45 to be sold into the trough B' through an opening formed in the case leading thereto, which trough guides the coin into grooves U'', formed in the ears U', which causes the coin to be grasped at its lower upper side by the finger 50 Y''. The coin thus connecting the arm Y, which is loose on shaft A, with arm U, which is fixed on shaft A; the coin is made to turn arm U, when the lever Y is operated. By pulling upon the knob 2, motion is communicated 55 to the shaft, which causes it to partially rotate the disks and segments secured thereon, by which rotation the receiver I is caused to be tilted by the cam P, and caused to discharge 60 the cigar that it contains onto the delivery-board, where the cigar may be conveyed to within the reach of the purchaser. The cigar, while in the receiver, keeps the tappet-rod T in its normal position, thus retaining the crank N in the notch formed in the lower end of the 65 lever W; but as the receiver reaches near the upward limit of its movement, and just before

70 discharging the cigar, the crank N is caused to disengage itself from the notch in the lever W and to slip off over the cut-away outer end thereof, which allows the lever W to be turned up a suitable distance by the spring X, to come in contact with the tappet-pin V' of the lever V, and to cause the outer bent end of said lever V, which normally closes the entrance of the grooves U'', and thus guards and retains the 75 coin in place, to disengage from below the edge of the coin, and to allow it to slide by its own gravity out from the grooves and into a suitable receptacle, or into the bottom of the case, as may be preferred. The curved portion of 80 the arm U is made to conform exactly in shape and size to the coin at which the price of the cigar to be disposed of is set, and consequently a coin of any other denomination would not operate the machine. In the event that no 85 coin or that an improper one is fed into the inclined trough, the rod 1 will only cause the lever Y to move, without imparting any motion to any other portion of the machinery, this being evident from the fact that the coin 90 would not be held between the grooves U'' and the finger Y'', which is necessary in order to cause the machine to operate. By this means it will readily be seen that dishonest persons would not be able to obtain cigars from the 95 case.

When the machine is to sell cigars at a price greater or less than it has been arranged for, the parts must be exchanged for others corresponding to the size of coin to be deposited.

I do not desire to limit myself to the exact construction of details as hereinbefore set forth, as it is obvious that many modifications may be made therein without departing from the spirit of our invention. For example, the 105 disks A might be dispensed with and arms used in their stead, though we prefer the construction here shown.

Having thus described our invention, we claim—

110 1. In a cigar-seller, the combination of the shaft A, the disks or arms D, secured thereto, segments E F and pivoted segment H, means for tilting said segment, the receiver I, spring L, delivery-board S, and an operating mechanism for moving the parts, substantially as shown.

115 2. In a cigar-seller, the combination of the shaft A, disks or arms D, secured thereto, segment F, rocking receiver I, spring L, cam P, 120 delivery-board S, and an operating mechanism for moving the parts, substantially as specified.

125 3. In a cigar-seller, the combination of the shaft A, disks or arms D, secured thereto, segments F, rocking receiver I, spring L, cam P, delivery-board S, tappet-rod T and shaft therefor, coin-receiving arm U, guard-lever V, suitable tripping mechanism therefor, and an operating mechanism for moving the parts, sub- 130 stantially as described.

130 4. The combination of the shafts A, disks

or arms D, secured thereto, segment F, rocking receiver I, spring L, cam P, delivery-board S, tappet-rod T, shaft M, crank N, tripping-lever W, guard-lever V, coin-receiving arm U, and an operating mechanism for moving the parts, substantially as set forth.

5. The combination of the shaft A, disks or arms D, secured thereto, segment F, rocking receiver I, spring L, cam P, delivery-board S, tappet-rod T, shaft M, crank N, tripping-lever W, guard-lever V, coin-receiving arm U, lever Y, having a finger, Y³, for grasping the coin, and an operating mechanism for moving the parts, substantially as specified.

15 6. The combination of the shaft A, coin-receiving arm U, secured thereto, lever Y, having finger Y³ for grasping the coin, guard-lever V, tripping mechanism therefor, cigar-receiver I, tilting mechanism therefor, delivery-board S, and an operating mechanism for moving the parts, substantially as shown.

25 7. The combination of the shaft A, coin-receiving arm U, secured thereto, guide-trough B³, a device for grasping the coin, guard-lever V, tripping mechanism therefor, cigar-receiver I, tilting mechanism therefor, and an operating mechanism for moving the parts, substantially as described.

30 8. The combination of the shaft A, coin-receiving arm U, secured thereto, ears U', having receiving-grooves U², guide-trough B³, a device for grasping the coin loose on shaft A, guard-lever V, tripping mechanism therefor, rocking cigar-receiver I, and mechanism for moving the parts, substantially as described.

35 9. The combination of the shaft A, coin-receiving arm U, secured thereto, ears U', having grooves U², guide-trough B³, lever Y, hav-

ing finger Y³, guard-lever V, tripping mechanism therefor, cigar-receiver I, tilting mechanism therefor, and an operating mechanism for moving the parts, substantially as shown and described.

10. The combination of the pivoted cigar-receiver, a suitable tilting device therefor, a coin-receiver that is rigidly secured to the shaft, a loosely mounted lever provided with a finger or other device for grasping the coin, a guard-bar for retaining the coin in the receiver, a lever for tripping the guard-bar, actuating mechanism therefor, springs or other devices for retaining the parts in their normal positions, and a bar or lever provided with suitable connections for operating the mechanism, substantially as specified.

15 11. The combination of an inclosing - case provided with an inclined feeding-board, a pivoted cigar-receiver, a suitable device for tilting said receiver, a coin-receiver that is rigidly secured to the actuating-shaft, an operating-lever provided with a device for grasping the coin, a guard-bar for retaining the coin in the receiver, a lever for tripping the guard-bar, actuating mechanism therefor, springs for returning the parts to their normal position, and a suitable operating bar or lever, all combined and arranged to operate substantially as shown and described.

In testimony whereof we affix our signatures in presence of two witnesses.
